UNITED STATES PATENT OFFICE.

THOMAS B. DRAPER, OF DETROIT, MICHIGAN.

COMBINATION DESK AND BED.

1,366,368.

Specification of Letters Patent. Patented Jan. 25, 1921.

Application filed October 22, 1917, Serial No. 197,773. Renewed June 12, 1920. Serial No. 388,668.

To all whom it may concern:

Be it known that I, THOMAS B. DRAPER, a subject of the King of Great Britain, residing at Detroit, in the county of Wayne and

5 State of Michigan, have invented certain new and useful Improvements in Combination Desks and Beds, of which the following is a specification, reference being had therein to the accompanying drawings.

10 In my companion application, filed under even date, there is disclosed a novel combination table and bed, the table being convertible with ease into a bed and the bed as readily reconverted into a table. Along the 15 same line and including somewhat similar operating mechanism is a combination desk and bed forming the subject matter of this application.

The present invention aims to provide a 20 flat top desk wherein the front and rear portions of the desk are adapted to be lowered to provide bed head and foot pieces. Of course the desk includes useful drawers and some of the drawers are shiftable with the 25 front and rear side portions of the desk so as to provide a comparatively low open structure and clearance for a spring frame, extensions thereof, and a mattress, all of which are concealed within the desk when 30 the same is in such form.

My invention still further aims to furnish a flat top desk with a novel shelf that may be easily and quickly swung from an active position to an inactive position and vice 35 versa, the shelf being designed for supporting a typewriting machine or other matter in front of the desk.

My invention further aims to provide a 40 piece of furniture of the above class where- in the parts are constructed with a view of reducing the cost of manufacture and at the same time retain those features by which durability, neat appearance, and ease of manipulating and assembling are secured. 45 With such ends in view, my invention fur- ther resides in the novel construction, com- bination and arrangement of parts to be hereinafter described and claimed.

Reference will now be had to the draw- 50 ings wherein—

Figure 1 is an end view of the desk partly broken away and partly in section;

Fig. 2 is a front elevation of the desk;

Fig. 3 is a side elevation of the bed as 55 formed from the desk, and showing parts thereof broken away

Fig. 4 is a plan of a portion of the same;

Fig. 5 is an end view of the desk, partly broken away and partly in section, showing the shelf in an active position; 60

Fig. 6 is a perspective view of a portion of the spring frame, and

Fig. 7 is a detail view of a caster that may be used in connection with the desk.

In describing my invention by aid of the 65 views above referred to, I desire to point out that the same are intended as merely illustrative of a combination desk and bed by which my invention may be put into practice, and I do not care to confine myself 70 to the precise construction and arrangement of parts shown. The following description is therefore to be broadly construed as including such substitute constructions and arrangement of parts which are the obvious 75 equivalent of these to be hereinafter referred to.

In the drawings, the reference characters A and B denote the front and rear portions respectively of a desk, and these portions 80 are adapted to be lowered on to a floor to provide bed head and foot pieces. The front portion of the desk carries with it a plurality of small drawers and a panel, the latter forming the foot piece of the bed. The rear 85 portion of the desk is devoid of drawers, but carries with it a flat desk top adapted to form the head piece of the bed, said flat desk top concealing the panel of the front portion of the desk when in such form. 90

Common to the front and rear portion of the desk is a bottom board 1 cut away, as at 2, so as to provide clearance for the limbs of a person sitting at the desk. On the bottom board 1 are large end drawers 3 and these 95 end drawers remain closed and stationary when the desk is converted into a bed. The end drawers 3 are slideable between parallel walls 4 and 5, the latter forming the side walls of the central limb space 6 of the desk. 100

Connected to the front and rear edges of the bottom board 1 at the ends thereof, by hinges 8^a are front legs 7, and rear legs 8, adapted to have the feet thereof swung under the bottom board, as shown in Fig. 3, so 105 that the upper ends of the legs or moldings carried thereby may rest on the floor with the legs in a horizontal position. The front legs 7 carry end panels 9 and the rear legs 8 carry end panels 10 and a rear desk panel 11, all of these panels being free to move 110 relative to the bottom board 1 and the large

end drawers 3 thereon. Hinged, as at 12, to the lower ends of the panels 10 are intermediate panels 13 and these intermediate panels can be lowered into parallelism with 5 the outer walls 4 after the front and rear portions A and B of the desk have been lowered.

The front legs 7 and the end panels 9 thereof can be swung toward the floor by 10 virtue of the hinges 8^a and carried above the large end drawers 3, at the front ends thereof, are partitions or walls 14, 28 and 15 coöperating in supporting small superimposed drawers 16 at the front portion of 15 the desk. Besides the drawers 16 there are the usual slides or shelves 17 and a panel 18 adapted to provide a bed foot piece, as shown in Fig. 3. An inclined stationary wall 19 provides a rear wall for the drawer structure, also for the upper part of the limb space 6 under the desk.

The outer walls 4 are provided with 20 spring frames 20 and these frames have rule or self locking points 21 for links 22 and said links are similarly connected to 25 extensions 23, said extensions, links and frames having lateral flanges to which a spring 24 may be connected, said spring having the ends thereof connected to transverse rods 25 supported by the extensions 23. The links 22, extensions 23 and spring 24 have been shown as folded in Fig. 1 with a mattress 26 in connection therewith and said mattress having a relatively thick central 30 portion with tapering ends suitably connected to the rods 25. To hold the links and extensions in a folded position, one of the rods 25 may be provided with hooks or 35 similar coupling means 27 adapted for engagement with the other of the transverse rods 25.

The upper drawer work of the desk has the vertical partition walls 28 in parallelism with the partitions 15 and the outer 40 sides of the partitions 28 are pivotally connected by side bars or links 29 to the inner sides of the walls 4, said side bars or links causing the upper drawer work to be properly shifted, when the front portion A of 45 the desk is lowered, this being accomplished without any danger of the upper drawer work impinging against the panel 18 which forms the bed foot piece. The front portion of the desk, including the legs 7 and the panel 18 may be swung downwardly in 50 an arc having for its center the hinges 8^a, but the upper drawer work swings without any tilting action as the links or side bars will maintain the small upper drawers constantly level while being lowered, the lowering movement being in synchronism with the legs 7 by reason of channel cam members 50 on the inner sides of the panels 9 receiving pins 51 carried by the partitions 60 65 or walls 28. As the panels 9 are lowered

the cam members will necessarily shift the pins 51 and in so doing automatically lift the upper drawer work off of the lower drawers and on to the floor.

To retard the movement of the front and 70 rear portions of the desk, when converting the desk into a bed, the inner sides of the end panels 9 and 10 are provided with inset segment shaped racks 30 adapted to be engaged by outwardly extending pins 31 carried by the walls 4. The racks 30 are somewhat similar to ratchet bars and together with the pins 31 constitute means for retarding the movement of the front and rear portions of the desk.

At the inner sides of the panels 9 and 10 are supports 32 and these supports are adapted to receive the ends of the transverse rods 25 of the spring frame extension, said supports being brought into position 85 to receive the rods when the front and rear portions of the desk are lowered.

It is thought that the manner of converting a desk into a bed and the bed into a desk will be understood without further description, and reference will now be had to another feature of my invention best shown in Figs. 2 and 5. The confronting sides of the partitions 15 and the walls 5 are provided with channel rails 33, said rails being 90 made in sections, some of which are carried by the partitions 15 for alinement with the other sections carried by the walls 5. Slidable in the rails 33 are the trunnions 34 of sets of levers 35 having the ends 95 thereof pivotally connected, as at 36, to a shelf 37. The trunnioned ends of the levers 35 have hooks 38 adapted to ride into engagement with pins 39 at the upper ends of the rails 33 and support the levers 35 with 100 the shelf 37 in a horizontal position protruding forwardly from a central drawer 40 in the front portion of the desk and between the upper end drawers. The confronting sides of the partitions 15 have 110 holdfast devices or latches 41 adapted to engage a lever 35 of each set and thereby prevent the shelf 37 from becoming accidentally displaced from an active position. When the shelf is not in use, it is adapted 115 to rest upon the bottom board 1 of the desk, as shown by dotted lines in Fig. 5, and when the shelf is raised to an active position, the hooks or cam members automatically ride into engagement with the pins 39 and throw the weight of the shelf or matter 120 thereon entirely upon said pins.

In connection with this piece of furniture, as well as the convertible table mentioned in the beginning, it is possible to use casters in 125 connection with the legs of the desk or the legs of the table, and by referring to Fig. 7 there is a portion of a leg 42, hinged as at 43 to a brace or bottom board 44. The leg 42 has an opening 45 and in the lower end 130

of the opening is a pivoted caster 46. Connected to the caster 46 is a pivoted link 47 that extends upwardly in the opening 45 and is pivotally connected to a bracket 48 extending into the opening 45 and carried by the brace or bottom board 44. In consequence of this manner of articulating the caster relative to the leg 42 and the brace 44, the caster may serve its purpose with the leg 42 vertical or horizontal, the caster always remaining vertical, as shown by full and dotted lines in Fig. 7.

What I claim is:—

1. In a desk, the combination of side walls 15 providing a limb space, a front portion hinged to said side walls adapted to be lowered on to a floor, a rear portion hinged to said side walls adapted to be lowered on to the floor, a desk top carried by the rear portion 20 of said desk and adapted to provide a bed head piece when lowered, a panel normally under said desk top and carried by the front portion of the desk to be lowered to form a bed foot piece, intermediate panels 25 between the front and rear portions of said desk and hinged to the rear portion thereof and adapted to be lowered to aline with said front and rear portions of said desk, and

means at the ends of said desk exposed by the lowering of said intermediate panels and 30 the front and rear portions of said desk adapted for supporting a spring between the bed head and foot pieces.

2. In a desk, the combination of front and rear portions adapted to be lowered on 35 to a floor, a desk top carried by the rear portion and adapted to provide a bed head piece, a panel normally under said desk top and carried by the front portion of said desk adapted to provide a bed foot piece 40 when lowered, stationary bottom end drawers in said desk, upper end drawers movable with the front portion of said desk and placed in front of said stationary bottom end drawers when said front portion is lowered, and spring frames in said desk having foldable extensions adapted to be extended over the movable drawers and supported by the lowered front portion of the desk.

In testimony whereof I affix my signature 50 in presence of two witnesses.

THOMAS B. DRAPER.
